UNITED STATES PATENT OFFICE.

JOSHUA RENNER, OF HAGERSTOWN, MARYLAND, ASSIGNOR OF ONE-HALF
TO THOMAS E. MITTAG, OF SAME PLACE.

AUTOMATIC RAILWAY-SWITCH.

SPECIFICATION forming part of Letters Patent No. 398,748, dated February 26, 1889.

Application filed January 4, 1888. Serial No. 259,775. (No model.)

To all whom it may concern:

Be it known that I, JOSHUA RENNER, a citizen of the United States, residing at Hagerstown, in the county of Washington and State 5 of Maryland, have invented certain new and useful Improvements in Devices for Operating Automatic Switches; and I do hereby declare the following to be a full, clear, and exact description of the invention, such as will enable 10 others skilled in the art to which it appertains to make and use the same.

My invention relates to certain new and useful improvements in devices for operating automatic railway-switches; and its object is 15 to furnish a device of this character which shall be economical in point of manufacture, and which shall combine durability and efficiency of operation with simplicity of construction. To effect this object I have de- 20 vised the arrangement of parts illustrated in the accompanying drawings, wherein—

Figure 1 represents a railway-switch provided with my improved automatic shifting apparatus, the switch being in the adjustment 25 necessary to complete the main line. Fig. 2 represents a locomotive-engine provided with an attachment for operating the shifting apparatus, and Figs. 3 and 4 represent enlarged detail views of said attachment.

Similar letters of reference indicate similar 30 parts throughout the several views.

Referring to the drawings, 1 1 indicates the main line or railway-track, and 2 2 a side track therefrom. 3 indicates a frog, and 4 a 35 switch, pivoted at 5, as indicated. The outer or free ends of the switch 4 are supported and secured upon a cross-piece, 6, for the purpose of moving said switch with the cross-piece. The cross-piece 6 is connected on opposite 40 sides of the track through the intermediary of the links 7 8 with the disks 9 10. The disk 9 is provided with two connecting or coupling rods, 11 12, which respectively extend to the disks 13 14, and the disks 13 14 45 are in their turn connected by links 15 16 to the pivoted arms 17 18. In like manner, as described, the disk 10 is provided with coupling or connecting rods 19 20, with disks 21 22, which are joined by the links 23 24 with 50 the arms 25 26.

The attachment for operating the shifting mechanism of the switch, illustrated in Figs. 4, 5, and 6, is attached, preferably, so as to be operated from the cab of a locomotive-engine, but, if desired, may, as will be readily understood, be attached to any other suitable portion of the rolling-stock. As illustrated in the drawings, it consists of a shaft, 27, supported beneath the engine by suitable journals or gudgeons and having rigidly connected to it 60 an end disk, 28. Through the shaft 27 extend pins 29 30, and upon these pins are mounted, so as to revolve freely, the disks 31 32. The end disk, 28, is connected by the coupling-rods 33 34 with a revoluble disk, 35, 65 located within the engine-cab and having an operating-handle, 36.

The parts of my invention being constructed and arranged as described, the operation of it is as follows: Assuming the main line to be 70 closed, as indicated in Fig. 1, the various portions of the shifting apparatus will occupy the positions indicated in that figure, and an engine or train approaching from either direction upon the main line will be free to pass on 75 over said line. If, however, an engine or train approaching from the right, with respect to Fig. 1, desires to pass upon the siding 2, the engineer or other attendant, by means of the handle 36, turns the disk 35, 80 thereby causing the connecting-arms 33 34 to revolve the disk 28 to a corresponding degree and with it the shaft 27, the movement being continued until one of the disks 31 or 32, according as the locomotive is advancing or 85 backing, is lowered to such position that it will strike against the said pivoted arm 25 as the engine passes over said arm. The arm 25 is accordingly rocked upon its pivot until it assumes a position parallel to the direction of 90 the rails of the main track. During this motion the link 23 partially revolves the disk 21, which in turn draws back the coupling-rod 19, revolves the disk 10, and through the intermediary of the link 8 moves the cross-piece 6 and with it the pivoted switch, thereby opening communication between the main track and the siding and permitting the engine or train to pass upon the siding. 95

It will be noted on reference to the draw- 100

ings that an engineer approaching from either direction on the main line is enabled to complete the main line should the switch be open; also to open or close it accordingly as he 5 wishes to pass in or out of the siding.

It is apparent that my shifting apparatus, as a whole, may be applied generally to the class of pivoted switches or the like—for instance, the well-known lock-switch, provided 10 with danger-signals—other than that illustrated in the drawings, by obvious modifications within the knowledge of those skilled in the art. I do not, therefore, desire to restrict myself to any particular kind of switch as 15 constituting an element of my invention.

It will be noted as characteristic of the eccentric-disks mounted upon the shaft of the engine-cab attachment that when one of said 20 disks is lowered the other is raised, thereby rendering it impossible for both to be in op-

erative position at the same time, thus securely guarding against damage which would result from the disks striking the arms 17 25 simultaneously.

Having thus described my invention, what 25 I claim as new therein, and desire to secure by Letters Patent, is—

A device for actuating an automatic switch of the kind described, consisting of a shaft, 27, carrying eccentrics 31 32, an end disk, 30 28, attached to said shaft, a disk, 35, provided with a hand-lever, and rods connecting the two disks, substantially as described.

In testimony whereof I affix my signature in presence of two witnesses.

JOSHUA RENNER.
